(57) **CLAIM**

The ornamental design for a card attachment, as shown and described.

DESCRIPTION

FIG. 1 is a perspective view of the card attachment.

FIG. 2 is a right side view of the card attachment, with the left side view being a mirror image thereof.

FIG. 3 is a top view of the card attachment.

FIG. 4 is a bottom view of the card attachment.

FIG. 5 is a front view of the card attachment.

FIG. 6 is a back view of the card attachment.

FIG. 7 is a perspective view of the card attachment of FIGS. 1-6 gripping a card with a retractable reel connected to the card attachment; and,

FIG. 8 is a perspective view of the card attachment of FIGS. 1-6 gripping a card with a neck lanyard connected to the card attachment.

The broken line showing of the clip in a position of use in FIGS. 7 and 8 are for illustrative purposes only and forms no part of the claimed design.
